CLAIM

The ornamental design for a boot, as shown and described.

DESCRIPTION

FIG. 1 is a bottom perspective view of a boot in accordance with the new design;

FIG. 2 is a top view thereof;

FIG. 3 is a bottom view thereof;

FIG. 4 is a left side view thereof;

FIG. 5 is a right side view thereof;

FIG. 6 is a front view thereof; and,

FIG. 7 is a rear view thereof.

The boot upper shown in broken lines in FIGS. 1-7 discloses the portion of the article that forms no part of the claimed design. The broken lines shown in each arch area of FIGS. 1 and 3 represent boundaries of the design with the lines themselves and the areas within them forming no part of the claimed design.
